UNITED STATES PATENT OFFICE.

EDWIN O. KRENTLER, OF DETROIT, MICHIGAN, ASSIGNOR TO KRENTLER-ARNOLD HINGE LAST COMPANY, OF DETROIT, MICHIGAN, A CORPORATION OF MICHIGAN.

PROCESS OF ASSEMBLING LASTS.

Original application filed April 24, 1922, Serial No. 556,150. Divided and this application filed April 5, 1924, Serial No. 704,506.

To all whom it may concern:

Be it known that I, EDWIN O. KRENTLER, a citizen of the United States, and resident of Detroit, in the county of Wayne and 5 State of Michigan, have invented an Improvement in Processes of Assembling Lasts, of which the following description, in connection with the accompanying drawings, is a specification, like letters on the 10 drawings representing like parts.

My present invention is an improved process of assembling the forepart and heel part in a shoe last, and is a divisional application of my prior case Ser. No. 556,150, 15 filed April 24, 1922.

An important feature of the improved last of my said prior application, wherein I have elected to claim the improved last as an article of manufacture, consists in the 20 improved process of building the last and assembling the wood and metallic members of the last parts. Heretofore it has been customary to put the forepart and heel part of a last, intended to be united with means 25 for relative movement, such as the well-known types of hinge last, link lasts, slide lasts or other distinct types of connecting devices permitting relative movement of the fore and heel parts for lengthening and 30 shortening same, in a form, jig, or the like, assembling each connecting element in its respective last part. Thereupon the final pivot pin, rivet or the like was applied.

In my present process I am enabled to 35 complete both the connection of the forepart and heel part, together with the assemblage of the unlocking and lock releasing elements, simultaneously, and by driving in the rivet to hold same. Furthermore, 40 I can if desired, unite the last members by a short rivet which will not extend beyond the outside limits of the metallic parts constituting the connecting means, and thereby assemble the entire metal hinge members, 45 then fitting this complete unit into the last parts, driving in the pins or rivets attaching the metallic members to forepart and heel part respectively, and thus complete the last. This form insures the complete 50 assembling of the unit outside the last parts. In the particular form of last herein shown, I can follow this method and then drive through the central pivot or pin, simultaneously removing the short pin or assembling pivot.

Referring to the drawings, illustrating a preferred embodiment of the invention,

Fig. 1 is a side view partly in cross-section, illustrating my improved last in extended position;

Fig. 2 is a view also partly in cross-section illustrating the last in flexed or broken position;

Fig. 3 is a fragmentary cross-sectional view on the line 3—3 of Fig. 1; and

Fig. 4 is a cross-sectional view on the line 4—4 of Fig. 1.

Referring to the drawings, 1 illustrates the forepart and 2 the heel part of a typical form of wooden last, as shown in the said 70 prior patents and my copending application, preferably divided by a line of cut giving the interlocking knuckle joint effect as shown by the projecting portion 3 on the heel part 2 and the abutting bearing 75 faces 4 and 5 to resist strains and stresses bottomward, the last being normally, in shoe manufacture, in upside down position. In the forepart 1 is bored a recess 6 to receive a tubular member 7, the latter being secured therein by a rivet or bolt 8. In the heel part is also formed a recess 9 in which a plate 10 is fitted and secured by a rivet 11. A tube 7 and plate 10 overlap, the tube having a slot to receive the overlapping or projecting portion of said plate 10, and the same are united by a pivot 12 passing through the knuckle projection 3, and on which pivot the forepart and heel 80 part of the last are hinged for relative 85 movement. The heel plate 10 has a forwardly extending projection 15, working through the slot in the forepart of the tube 7. This tubular member 7 is also formed with the slot portion open at the top 90 slightly, as illustrated at 16, 16, Fig. 4, and straddling the heel plate hinge member 10 is my combined locking, operating and 95 unlocking device. This device consists in a metallic hinge member comprising a pair 100 of arms or lugs 17, 17, suitably spaced to straddle the heel plate 10, being united at the outer or top portion 20 and also at the forward part 21. The latter may be and 105 preferably is formed as a block or bolt of suitable diameter to fit slidingly the tube 7, and may be integral with the arms 17, 17, or secured thereto by a rivet 22. The arms 17, 17, are preferably formed in substantially triangular or V-shaped contour, 110

extending downwardly each side of the plate 10, and about the projection 15, thus holding the locking portion 21 forwardly of the pivot 12, each of said arms 17 having slots 24 through which the pivot 12 passes.

In the fore part 1 I cut or form a kerf 25 of sufficient depth and width to receive the locking and unlocking devices so far as 10 the width of the arms 17, 17, is concerned, when the same is moved forwardly, the latter sliding on the pivot 12.

With the last constructed as thus far described, and in extended position as shown 15 in Fig. 1, a slight pressure on the handle portion 20 of the locking and unlocking device will act to slide the same forwardly for the limit allowed by the length of the slot 24 and the diameter of the pivot 12, 20 thus moving the interlocking portion 21 out from under engagement with the overhanging projection 15 on the heel plate 10, thereupon permitting the heel and fore parts to be readily flexed. Upon repositioning 25 the last in extended position, a slight movement of the locking and unlocking device or member rearwardly or to the right viewing the figures in the drawing, serves to catch the portion 21 under the part 15 and 30 lock the same bearing between the lower part of the tube 7 and said part 15 of the heel plate. The lower contacting face of this projection 15, where it engages the portion 21, may be and preferably is slightly 35 beveled, to permit a tightening action between the contacting faces in the locking action, when the device is moved to the right, viewing the figures and therefore in 40 locked position. This permits compensation for looseness and wear and holds the lower faces 4 and 5 always firmly in contact, irrespective of a slight looseness in the 45 hinge parts or wear in the rivets.

In order to make the locking action automatic as well as to facilitate the action of 45 the same, and as well, also, as to maintain the parts in firm and rigid position, I provide a coiled spring 30, fitting within the tubular member 7 and bearing between the 50 rivet 8 and the interlocking portion 21 of the locking and unlocking device.

This spring 30 acts normally and constantly to force the locking and unlocking device and particularly the portion 21 forwardly and hence when it is in engagement 55 with the projection 15, the last will be held under a tightening tension, the space 31 being cut back considerably to allow for such continuous tension during a considerable extent of such looseness in the wear of the last parts.

In assembling the last the fittings are readily applied and connected, the tubular and plate hinge members being fitted and

pinned as is usual in this type of last. 65 Thereupon the locking and interlocking member is applied, straddling the hinge plate 10, the spring 30 is fitted if a spring is desired, and the parts are joined and the pivot pin 12 driven in, thereby automatically securing the fore and heel parts together, as well as the locking and interlocking member, said pin passing through the slot 24 therein. 70

It will be understood that I may utilize 75 a short pivot as indicated in dotted lines, Fig. 3, at 50, the same terminating at the outer surfaces of the tube 7, as shown at 51 and 52. This enables these hinge members to be thus assembled as a unit, then applied to the fore part 1, the retaining rivet 8 driven in, or with the tube 7 and retaining pivot 8 first applied to the fore part 80 and then assembled with the spring 30, movable locking member 21, link 10 and short pivot 50 thus uniting the hinge members. Thereupon the heel part 2 is fitted and the retaining rivet 11 applied, thus completing the assemblage of the last. In the form 85 just described, the short tube 50 may be concealed within the last parts, or if desired, and as also herein illustrated, the longer pivot pin 12 may then be driven through, the last parts being bored for this purpose as above explained, and the short 90 pivot 50 simultaneously driven out with the driving in of the pivot 12. By this method also the last parts are assembled substantially as a unit, and the connecting elements, locking, unlocking and releasing trigger 20 also simultaneously assembled. 95 100

The operation of the last will be readily understood from the foregoing description and is identical with that of my said co-pending application. The last is easily 105 unlocked by a simple pressure on the portion 20 of the locking and unlocking device, thereby releasing the locking engagement 110 of the portion 21 from its position, when the last is extended as shown in Fig. 1, and thereupon the fore part and heel part are readily flexed and the last can be removed from the shoe. Reverse movement 115 of the hinge parts automatically locks the last in extended position, when a spring is employed, or if a spring is not employed, a slight reverse movement of the locking and unlocking device serves to move the portion 21 into locked engagement.

I believe that my present invention wherein a last is devised and constructed by a process which permits the uniting of the fore part, heel part, and hinge members simultaneously with the assembling and permanently securing of a locking and unlocking element is new, and I wish to claim this process of manufacture broadly herein, this particular feature being common with the 120 125

last of my present invention and my co-pending application, Ser. No. 553,616, filed April 17, 1922.

My invention is further described and 5 defined in the form of a claim as follows:

The improved method of manufacturing a last for use in the manufacture of boots and shoes, having a fore part and heel part relatively movable, which consists in 10 structuring the forepart and heelpart with recesses to receive connecting members, including positive locking means and lock releasing means, utilizing a temporary retaining element for temporarily assembling

the connecting means and interlocking and releasing elements, applying the connecting, interlocking and releasing elements to the fore part and heel part while thus temporarily assembled, then completing the manufacturing operation by driving a retaining element acting to unite the last connecting and interlocking elements while simultaneously removing the temporary retaining element. 15 20

In testimony whereof, I have signed my 25 name to this specification.

EDWIN O. KRENTLER.
